UNITED STATES PATENT OFFICE.

HARRY F. STRATTON, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRICAL CONTACT.

1,045,212.

Specification of Letters Patent. Patented Nov. 26, 1912.

Application filed August 19, 1912. Serial No. 715,761.

To all whom it may concern:

Be it known that I, HARRY F. STRATTON, a citizen of the United States, residing at Cleveland, in the county of Cuyahoga and State of Ohio, have invented new and useful Improvements in Electrical Contacts, of which the following is a specification.

My invention relates to electrical contacts.

In particular it relates to contacts used in 10 drum type controllers in which a relatively stationary contact is arranged to be engaged by a movable contact revolved under it in any of the well known ways.

One of the objects of my invention is to 15 provide a contact universally movable so as to enable its full surface contact to engage a coöperating contact which may be of irregular shape.

Another object is to preserve the full 20 surface contact between the coöperating contacts as either or both of them wear down, especially if one portion of either contact wears faster than another.

Other advantages will be obvious as 25 pointed out in the following description and claims.

To more fully explain my invention I will refer to the accompanying drawings, of which—

30 Figures 1 and 2 are elevations and part sections of the device, and Fig. 3 is an end view of the contact tip, showing the adaptability of the contact finger to a worn or irregular shaped movable contact.

35 Referring to the drawings, 1 is a partial view of a revolving drum which carries a contact 2 adapted to engage the tip 3 of the relatively stationary contact finger 4. The finger 4 is supported by a holder 5 mounted 40 on a support 6. The holder 5 is adapted to receive an electrical conductor clamped by the nut 7, and the current is carried from the holder 5 to the finger 4 through a flexible connection 8. The finger 4 is held in 45 position against the projection 9 of the holder 5 and the stud 10 by means of the compression spring 11, which is held in its compressed position by a cotter pin 12 passing through the pin 13 which is screwed into 50 the holder 5, as shown in the drawing. The stud 10, which supports the back end of the finger 4, is formed into a spherical shape at the point of contact with the finger, and the finger 4 is provided with a spherical shaped 55 recess to engage the stud 10 at this point,

so that the finger may revolve about the point of contact with the stud 10 as a pivot when the contact 2 engages the finger tip 3.

As the contact 2 comes into engagement with the finger tip 3, the forward end of the finger is raised off of the projection 9 about the stud 10 as a pivot, and if the contact 2, or the lower surface of the tip 3, is not exactly true, the finger 4 will also be tipped to one side or the other about the spherical surface of the plug 10 so as to make full contact between the parts 2 and 3. This arrangement is indicated in Fig. 3, which shows the contact 2 to be worn away to a greater extent on the left-hand side than on the right, but the finger 4, with its contact tip 3, adapts itself to the irregular surface of the contact 2 by reason of the pressure of the spring 11 revolving the finger in the position shown. This arrangement is of 75 particular advantage when a new finger is placed in an old controller, for any reason, in which the contacts on the drum have worn to any considerable degree. When the new finger is put in place it will readily 80 adapt itself to the contact surface of the contact 2 regardless of its condition.

The pressure between the contacts can be regulated by adjusting the stud 10 up and down. A spring clip 14 is provided which 85 bears against the hexagon sides of the stud 10 and holds it in whatever position it is adjusted.

I have shown the finger 4 constructed of a metal bar of channel section, as shown in 90 Fig. 2, but it is obvious that the finger may assume other forms as desired.

I claim—

1. In an electrical contact, a holder, a contact member supported thereby, a spherical bearing for the contact member carried by said holder, and a spring for holding the contact member on the said bearing.

2. In a contact device, a holder, a contact member, means for supporting said contact member near its ends, a spring for holding the member against the supporting means, and a spherical bearing between the contact member and one of said supports.

3. In a contact device, a contact member, a coöperating contact which supports one end of said member, a spring for holding said member against said coöperating contact, and a spherical support for the other end of said member.

4. In a contact device, a contact member, a coöperating contact which supports one end of said member; a spring for holding said member against said coöperating contact, a spherical support for the other end of said member, and means for adjusting said support.
5. In a contact device, a contact member, a coöperating contact which supports one end of said member, means for holding said

member against said coöperating contact, and a support for the other end of said member which allows said member to turn about its longitudinal axis.

Signed at Cleveland, Ohio, this 16th day 15
of August, 1912.

HARRY F. STRATTON.
